UNITED STATES PATENT OFFICE.

JOANES B. VERMEULEN, OF LETCHER, SOUTH DAKOTA.

TRIPPING DEVICE.

Application filed October 23, 1923. Serial No. 670,360.

To all whom it may concern:

Be it known that I, JOANES B. VERMEULEN, a citizen of the United States, residing at Letcher, in the county of Sanborn and State 5 of South Dakota, have invented certain new and useful Improvements in a Tripping Device, of which the following is a specification.

This invention appertains to double barrelled shot guns or other double barrelled fire arms and the primary object of the invention is the provision of a novel means for permitting the firing of first one barrel and then the other by the use of an improved 15 single trigger arrangement.

Another prime object of the invention is the provision of a tripping device for double barrelled guns in which a single trigger is utilized for firing first one barrel and then 20 the other, thereby eliminating the necessity of the person using the device changing his grip on the arm, thereby aiding in accurate shooting.

A further object of the invention is the 25 provision of an improved tripping device for double barrelled firing arms embodying a single trigger and a ratchet disk operated by the trigger for rotating a shaft, which in turn carries means for operating the firing mechanism for one barrel and then the firing mechanism for the other barrel.

A further prime object of the invention 30 is the provision of novel means for holding the shaft carrying the means for operating the firing mechanism for the barrels against accidental rotation after the operation thereof through the medium of the ratchet disk and trigger.

A still further object of the invention is 35 the provision of an improved tripping device embodying a single trigger for double barrelled shot guns and the like, which will be durable and efficient in use, one that will be simple and easy to manufacture and one 40 which can be incorporated with fire arms at a minimum cost.

With these and other objects in view, the 45 invention consists in the novel construction, arrangement and formation of parts, as will be hereinafter more specifically described, claimed and illustrated in the accompanying drawings, in which drawings:

Figure 1 is a fragmentary longitudinal section through a double barrelled shot gun 50 illustrating the improved tripping device incorporated therewith.

Figure 2 is a substantial horizontal section through the gun taken on the line 2—2 of Figure 1.

Figure 3 is a transverse section through 60 the gun taken on the line 3—3 of Figure 1.

Figure 4 is a detail perspective view of the ratchet disk for rotating the firing shaft by the use of a single trigger.

Figure 5 is a detail perspective view of 65 the shaft, and

Figure 6 is a detail perspective view of 70 the member carried by the shaft for actuating the firing mechanism for one barrel and then the other.

Referring to the drawings in detail, wherein similar reference characters designate corresponding parts throughout the several views, the letter A generally indicates fire arm embodying a pair of barrels 10 and 11 and B the improved tripping mechanism for firing first one barrel and then the other through the medium of a single trigger.

Each barrel 10 and 11 is provided with 80 a firing pin 12 and located in rear of each firing pin is a hammer 13 therefor. Each hammer 13 is rotatably mounted upon a transversely extending shaft 14 located directly in rear of the barrels 10 and 11. Each hammer 13 below the pivot point thereof is provided with detents or teeth 15 and a rearwardly extending arm 16.

The improved tripping mechanism B for 90 the hammers 13 includes a shaft 17, which in this instance is disposed in a vertical plane and directly between and in rear of the hammers 13. This shaft is preferably mounted for rotary movement and is provided with a longitudinally extending slot 18 to permit the keying of the ratchet disk 19 and firing member 20 thereto by means of a suitable key 21. The firing member 20 is preferably located above the ratchet disk 19 and this ratchet disk is provided with a plurality of spaced ratchet teeth 21, which are located adjacent to the periphery thereof.

The trigger 22 is pivotally mounted 95 upon a suitable pivot pin or the like 23 directly in rear of the shaft 17 and carries a pivoted dog or pawl 24 which is adapted to successively engage the teeth 21 of the ratchet disk 19 for bringing about the rotation of the shaft 17. A contractile coil spring 25 is connected with the trigger 22 above the pivot pin 23 thereof for normally holding the same in firing position so that 100 105 110

the dog 24 will be swung back into engagement with another ratchet tooth 21 after the same has been actuated.

The firing member 20 includes a hub 26 and radially extending actuating blades 27, 28 and 29. As shown these blades are twisted into an arcuate shape in order to effectively bring about the operation of the hammers as will be hereinafter more fully described.

Arranged in rear of and below the plane of the shaft 14 is a shaft 30 on which is rockably mounted the trip arms 31 and 32. The trip arm 31 engages one hammer 13, while the trip arm 32 engages the other hammer 13 and these trip arms normally prevent the swinging movement of the hammers into engagement with the firing pins 12. The rear terminals of the trip arms 31 and 32 are provided with inwardly directed lugs 33 which lie in the path of the blades 27, 28 and 29 formed on the firing member 20. Disposed in rear of the shaft 17 is a transversely extending shaft 34 on which is rockably mounted the hammer operating members 35 and 36. These members 35 and 36 extend forwardly toward the hammers and are located directly above the trip arms 31 and 32. These members 35 and 36 are bifurcated to provide a pair of diverging actuated arms 37 and 38. The arm 37 extends forwardly beyond the lower arm 38 and is connected to the arm 16 formed on the hammer by means of a link 39. The lower arm 38 is provided with an arcuate depending foot 40 which normally rests upon the upper surface of the trip members 31 and 32 adjacent to the trip wheel 20.

In order to normally hold the trip wheel 20 against accidental movement as the same has been actuated by the trigger 22 an expansion spring 41 is coiled about the shaft 17 and the upper end of this spring bears against the frame of the gun, while the lower end thereof frictionally rests upon the said wheel 20.

In use of the improved fire arms, the trigger 22 is pulled back in the usual manner, which will force the pawl 24 forwardly and rotate the ratchet disk 19. The rotation of the ratchet disk 19 will rotate the shaft 17 and the wheel 20. This will move the blade 27 into engagement with the inner end of the trip arm 31 and raise the same

and move the forward end of the trip arm 55 below the hammer on the right-hand side and out of engagement with the teeth formed thereon. The raising of the inner end of the trip arm 31 will lift the operating member 35 and thus actuate the hammer 60 through the medium of the link 39 and forcibly move the same into engagement with its firing pin. The blade 28 on the wheel 20 will now be disposed adjacent to the inner end of the trip arm 32 and when the trigger 65 22 is again pressed the shaft will be again rotated and the trip arm 32 thus causing the operation of the left-hammer 13 and causing the firing of the left-hand barrel.

The gun can now be broken for the 70 ejection of the fired cartridges and permit the new cartridges or shells to be placed in position.

From the foregoing description, it can be seen that I have provided an improved 75 tripping device for double barrel shot guns and the like which will permit the operation of first one barrel and then the other by the use of a single trigger.

Changes in details may be made without 80 departing from the spirit or the scope of this invention.

What I claim as new is:

In a firearm, a pair of barrels, a firing pin for each barrel, a hammer for each firing pin, a pivoted trip arm for each hammer, an operating member for each hammer including a pair of diverging arms, means connecting one arm to each hammer, the other arm engaging the trip arm, a rotary 90 shaft arranged between the trip arms and operating members, a ratchet disk keyed to the shaft, a trip wheel including a plurality of radiating blades keyed to the shaft, means for normally holding the trip wheel in a 95 predetermined position against accidental movement, a single trigger, means normally holding the trigger in a predetermined position, and a pawl carried by the trigger for engaging the ratchet disk for bringing 100 about the rotation of the shaft upon each time the trigger is pulled.

In testimony whereof I affix my signature in presence of two witnesses.

JOANES B. VERMEULEN.
